UNITED STATES PATENT OFFICE.

LOUIS WOJIDKOW, OF BROOKLYN, NEW YORK.

DESIGN FOR A KETTLE-STAND.

SPECIFICATION forming part of Design No. 25,475, dated May 12, 1896.

Application filed April 11, 1896. Serial No. 587,220. Term of patent 3½ years.

To all whom it may concern:

Be it known that I, LOUIS WOJIDKOW, a citizen of the United States, residing at Brooklyn, in the county of Kings and State of New York, 5 have invented and produced a new and original Design for a Stand for Kettles, of which the following is a specification, reference being had to the accompanying drawing, which shows a perspective view of the same.

10 The leading feature of my design consists of skeleton brackets or supports, each formed of two inwardly-curved uprights joined at their upper end with a curved cross-piece and near their lower free end with a loop or

15 scroll, said brackets resting on a fanciful base. A represents the brackets, each formed of

the two inwardly-curved uprights B B, joined at their upper ends by the curved cross-piece C. Near their lower free ends the uprights B are joined by the scroll D. These brackets 20 are supported on the circular base E, the lower depending edge F of which is scalloped, said base being mounted on the fanciful legs G, as shown.

What I claim is—

25 The design for a kettle-stand substantially as herein shown and described.

LOUIS WOJIDKOW.
